UNITED STATES PATENT OFFICE.

DANIEL F. HART, OF NEW YORK, N. Y.

FURNITURE ELEMENT FOR SHOE FITTING.

Application filed March 30, 1923. Serial No. 628,878.

To all whom it may concern:

Be it known that I, DANIEL F. HART, a citizen of the United States, and a resident of the city of New York, borough of Manhattan, in the county of New York and State of New York, have invented a new and Improved Furniture Element for Shoe Fitting, of which the following is a full, clear, and exact description.

- 10 This invention relates to articles of furniture, by which in the present instance is meant a fitting or furniture utensil particularly adapted to form a component part of a complete furniture unit, such as a furniture unit comprising a chair or stool on which a customer in a shoe store is preferably to be seated,—the article of furniture, as the term is used in the specification, comprising essentially a foot-rest board for use 20 in connection with a foot-length measure in such a store. It is appreciated in the art that such a board may be mounted to be offset at a slight angle to the horizontal, from a stool or chair structure as aforesaid, as a result of 25 being secured in some suitable way or of being integrally formed with a part of a leg element or the like of such a structure. It will be understood, however, in this connection, that the new board may be furnished 30 as a complete stool element, in that case desirably to carry three or more legs fixed to and below the board.

The prime object of the present invention is to provide a new and improved combination of board and measure members, and one particularly having the advantages of extreme convenience and time and motion-saving efficiency in use, a rugged yet lightweight construction, and such a construction 40 which will be enduring especially in the sense that the new article will not ever become materially warped or misshapen (although the article is preferably constructed in the main of wood so far as the board is 45 concerned).

A further object of the invention is to provide an article as just defined, but one which may be constructed and sold at a comparatively small figure, and yet will be of such de 50 luxe appearance as to be a distinct ornament as well as a utilitarian fixture for a shoe store of fastidious clientele.

According to the present invention, there is provided a fixture including a board and

having means for nesting the major portion 55 of the measure while concealing said portion thereof from view; this nesting means including (1) a wide slot cut in one side edge of the board and running from end to end thereof, (2) means wholly within the slot, 60 preferably a laterally arranged leaf-spring and hence a resilient instrumentality, for impositively retaining the measure in its nested and concealed location, yet for permitting the measure to be inserted in the 65 slot and removed therefrom without material impediment to such movement of the measure relative to the slot. Preferably, the nesting means includes also (3) stop means, 70 preferably wholly exterior to the slot, and adapted positively to hold the measure nested in its slot following a combined swinging and longitudinal sliding movement of the measure to dispose the same completely within the slot as 75

Various other objects and advantages of the invention will be expressly pointed out and indicated hereinafter.

The invention will be best understood from a consideration of the following detailed description when taken in connection with the accompanying drawing forming part of this specification; with the understanding, however, that such drawing illustrates, merely by way of example, one possible embodiment of the invention, and that the invention is not confined to any strict conformity with the showing in the drawing, but may be changed and modified so long as such changes and modifications mark 90 no material departure from the salient features of the invention as expressed in the appended claims.

In said drawing,

Fig. 1 is a perspective view of the new 95 article of furniture, with the measure wholly nested;

Fig. 2 is a top plan view on an enlarged scale, of the lower of the two wood sheets forming the board;

Figs. 3, 4, and 5 are vertical sections taken respectively on the lines 3—3, 4—4 and 5—5 of Fig. 2, these sectional views being on even a more enlarged scale than the showing of Fig. 2; and

Fig. 6 is a perspective view of the measure detached and having the calibrations on its long length uppermost contrary to the ar-

angement when the measure is nested in the board as indicated in Fig. 1.

Referring now to the details of the drawing, the board is indicated at 7. This board, referring to Figs. 2 to 5, is preferably formed of two wooden sheets or boardplies 8 and 9.

The slot of the nesting means, such slot being indicated at 10, is established by planing out somewhat less than one-half the width of ply 8 along the entire length thereof. The only other wood-working operations required on ply 8, other than to shape its uniplanar bounding faces and to shape one of its end edges as illustrated and as marked 8^a in Fig. 2, is to use an ordinary drill or rotary tool to cut a semi-circular recess 11 as indicated in Fig. 2.

The only finishing operations required relative to upper ply 9 are to shape its similar end edge as indicated at 9^a in Fig. 1 and to drill or otherwise cut a cylindrical recess, indicated in dot-and-dash lines at 12 in Fig. 2, in its undersurface where such undersurface is to overlie or rather form the roof wall of slot 10.

These recesses 11 and 12 are for the purpose of nesting permanently, and in concealed but yet always effective position, an impositive retaining means of a resilient nature, here including a leaf-spring 14. As will be seen most clearly from Fig. 3, this leaf-spring has a downwardly bowed intermediate portion 14^a for frictionally engaging a face of the long length 15^a of a measure 15 as shown in Fig. 6, a terminal portion 14^b to be anchored in recess 11 by means of screws 16 (although it will be understood in a moment that even brads may be substituted for these screws), and a reduced slightly up-hooked free end 14^c always to be more or less projected into under-cut surface 12 when the two plies 8 and 9 are secured together.

These two plies are secured together, to constitute a complete board as shown in Fig. 1, by the use of furniture glue and a clamping means applied while the glue is setting, as is familiar in the cabinet-making art, and from this statement it will be understood that, the leaf-spring 14 being anchored at one end in recess 11 as above described before the upper ply is laid over the lower one, the screws 16 may be brads as aforesaid and yet serve their appointed functions perfectly.

The two plies are cut so that when they are glued together they will have the grain of one ply at an angle to the grain of the other; and preferably, each ply is made up of a plurality of sub-plies having the seams of adjoining sub-plies angularly offset. This construction not only makes for economy, as permitting quite thin wooden strips to be used, but defeats any tendency what-

ever of a warping of the board so as to destroy its finished appearance and efficiency and the functioning as devised of the nesting means and its appurtenances.

The just-described protection for the board against warping is further augmented by a means now to be described, and preferably forming also a further appurtenance (additional to spring 14) of the nesting means.

In this connection, a stop means is provided, for bracing the floor and roof members of the slot 10 at the corners thereof marked C in Fig. 2, such stop means being located wholly outside the slot, as contradistinguished from the retaining means constituted by spring 14 and located wholly within the slot. Here such stop means is provided so as to have considerable decorative effect and at the same time to represent maximum economy. Said stop means includes three vertically arranged staple devices 16 and 17 arranged as best shown in Fig. 2. These are desirably made of round brass wire, nickel-plated; which enhances the generally attractive appearance of the new article when the two plies 8 and 9 thereof are constructed of or finished in oak, mahogany or the like, and the upper ply 9 carries the conventional dark-gray corrugated rubber pad 18.

Measure 15, it will be noted, carries at one end of its long length 15^a an upstanding terminal length 15^b adapted to act as a heel rest when the measure is laid on the top of pad 18 in the manner well understood in the art. However, as shown clearly in Figs. 1 and 4, such measure, when nested in its nesting means, is reversed to have its portion 15^b depending and hence to have its calibrated surface underneath and out of possible contact with the bowed portion of spring 14.

To remove the measure from the board, when such measure is completely nested as shown in Fig. 1, a pull toward the observer on portion 15^b of the measure, to advance the far end of the measure toward and beyond the nearest staple 16, and then a combined sliding and swinging movement of the measure, in the direction of the arrow M of Fig. 1, snaps the measure entirely free of the nesting means. To return the measure to its fully nested position, the same is arranged to have the calibrated face of its long length underneath, and the end of the measure marked 15^c in Fig. 6 is inserted into slot 10 at any point along its length between spring 14 and staples 16, and then, with the measure extended desirably at an oblique angle relative to the wide mouth of the slot along the side edge of the board, the measure is swept into fully nested position as indicated in Fig. 2, by a combined swinging and sliding movement thereof relative to the slot.

Variations may, of course, as hereinabove indicated, be resorted to within the scope of the following claims.

I claim:

- 5 1. An article of furniture for use in shoe stores, comprising a foot-rest board having a slot in one of its side edges, said slot extending from the front to the rear of the board and adapted to receive a foot rule substantially wholly therewithin, and spring means within the slot to restrain the rule within the slot.
- 10 2. An article of furniture for use in shoe stores, which comprises a foot board having a slot of considerable width in one of its side edges, said slot adapted to receive a foot measure substantially wholly therewithin, a spring disposed within the slot near the front edge of the board, said spring adapted to engage a foot rule when inserted therein to engage a foot rule when inserted therein to hold it in the slot, and a pin disposed across the rear portion of the slot to prevent that end of the rule from coming out of the slot.
- 15 3. An article of furniture for use in shoe stores, which comprises a foot board having a slot of considerable width in one of its

edges, said slot extending from the front to the rear of the board, a foot rail adapted to be substantially wholly therewithin inserted in said slot, a stop means disposed across the slot at the rear end thereof to confine the rear end of the foot rule within the slot, and a spring disposed in the slot near the front end thereof to engage the front end of the foot rule to restrain it from removal from the slot.

4. An article of furniture for use in shoe stores, which comprises a foot-rest board having a slot in one of its side edges adapted to receive a foot rule substantially wholly therewithin, and means associated with the open edge of the slot to restrain the rule therewithin.

5. An article of furniture for use in shoe stores, which comprises a foot-rest board having a slot cut in one of its side edges, said slot extending from the front to the rear of the board and adapted to receive a foot rule substantially wholly therewithin, and a barrier or pin disposed along and adjacent to a portion of the open edge of the slot to restrain the foot rule therewithin.

DANIEL F. HART.
